UNITED STATES PATENT OFFICE.

CLARENCE E. PRATT, OF DALLAS, TEXAS.

ENGINE.

1,286,189.

Specification of Letters Patent. Patented Nov. 26, 1918.

Application filed November 22, 1915. Serial No. 62,692.

To all whom it may concern:

Be it known that I, CLARENCE E. PRATT, a citizen of the United States, residing at Dallas, in the county of Dallas and State of 5 Texas, have invented a certain new and useful Improvement in Engines, of which the following is a full, clear, concise, and exact description, reference being had to the accompanying drawings, forming a part of 10 this specification.

My invention relates to engines which employ governors. In practising my invention the engine governors are desirably located within the crank cases to be effectively 15 lubricated by the oil which is dashed about in engine operation.

In accordance with one feature of the invention, the governor is located on the crank pin side of the crank desirably by being suspended from the crank pin of the engine either directly or through the medium of a 20 crank pin extension which constitutes a pivotal support for the governor. The invention also contemplates the use of an arm 25 that constitutes a mounting for the stops between which the governor arm may oscillate and which stops serve to define the range of operation of the governor.

In accordance with another feature of the 30 invention the governor valve driving reach rod that connects the governor with the engine valve is also placed within the crank case where it may be effectively lubricated.

In accordance with another feature of the 35 invention the bearing for the rocker arm is also inclosed within the engine case to adapt it for lubrication which is also true of the portion of the rocker arm intervening between its mounting and the connection of 40 such arm with the reach rod.

I will explain my invention more fully by reference to the accompanying drawings showing the preferred embodiment thereof and in which Figure 1 is a side view partially in section of an engine equipped in accordance with the invention; Fig. 2 is a view on line 2 2 of Fig. 1; and Fig. 3 is a view on line 3 3 of Fig. 1.

Like parts are indicated by similar characters of reference throughout the different figures.

The engine shown is of a type which is well known, a high speed self-oiling steam engine. The base 1 of the engine supports 55 the engine frame 2 at whose forward end there is carried the usual engine cylinder 3

and valve chest 4 while at whose rear end there is provided a bearing 5 in which the main engine shaft 6 is turned. The piston within the cylinder 3 has the usual piston rod 60 7 in connection with the crosshead 8, the crosshead having the usual connection with one end of a pitman 9 whose other end is connected with a crank pin 10. This crank pin is mounted upon a crank 11 which is in fixed 65 relation with the shaft, a balancing counterweight 12 being also attached to the arm. The counterweight is desirably in the form of a segment of a circle that is concentric with the shaft, this counterweight dipping 70 within the oil 13 (or a mixture of oil and water) that is provided in the bottom of the crank case for the purpose of splashing the oil and casting it forwardly to oil the crosshead and other parts of the engine at the 75 cylinder end thereof and to deposit oil upon the bearing 5, there being provision for returning the oil to the crank pit so that it may be used over and over again. The level of the oil is desirably sufficiently high to 80 enable the outer end of the crank arm also to dip into the oil on each revolution of the engine shaft whereby the crank pin is thoroughly lubricated. Such systems of lubrication are well known to those familiar 85 with the art.

A stop carrier 14 is in rigid relation to the crank arm and therefore rotates with the engine shaft. This stop carrier carries abutments 15 and 16 between which an end of an 90 inertia bar 17 may oscillate, the position of the inertia bar regulating the operation of the steam valve to regulate the speed of the engine, as those who are familiar with the action of governors will understand. The 95 inertia bar 17 is pivotally mounted at one side of its center of gravity upon a pin 18 which is located at the crank pin but is eccentric with respect thereto. A coiled spring 19 is anchored at one end to the stop carrier 100 and at the other end to the inertia bar, this spring opposing the centrifugal action of the inertia bar to enable the bar to be positioned to regulate the action of the steam valve. The valve rod 20 is pivotally connected with 105 the upper end of a rocker arm 21 intermediately pivoted at 22 upon and within an enlargement of the engine case, the mounting for the rocker arm being positioned to be reached by some of the oil which is cast upwardly by the counterweight 12 and the crank arm 11. The lower part of the rocker 110

arm is pivotally connected with one end of the reach rod 23, the other end of this reach rod being pivotally connected with the inertia bar. By positioning the shaft or pin 5 18 eccentric to the crank pin 10 I obtain advantageous lead conditions in that the shaft or pin 18 is positioned 5 to 10 degrees ahead of the rotation of the center of the crank pin. The reach rod operates in a vertical plane 10 parallel with the plane in which the pitman 9 operates. The reach rod and its connections with the rocker arm and inertia bar are thus located within the engine case so as to be reached by the oil or other lubricant 15 which is cast upwardly by the rotating parts within the crank case. It will be observed that the shaft driving crank is upon the inner end of the shaft that projects from one side of the crank, the crank pin being upon 20 the opposite side of the crank and carrying the governor. By this arrangement the governor may operate across the inner end of the shaft without interference from the shaft.

25 The quantity of oil within the crank pit is also desirably sufficient to enable the inertia bar itself to scatter or distribute the oil upon its own working parts as well as upon other moving parts of the engine. The engine case 30 may be closed in any suitable manner, the case desirably including a hood portion 24 at the shaft end of the engine, this hood desirably being made comparatively light so that it may readily be removed and replaced, 35 though its connection with the balance of the engine case is of such a nature as to constitute a completely closed case from which the lubricant may not escape in the operation of the engine. By locating the governor on the 40 crank pin side of the crank a straight bar inertia governor may be supported upon the crank whereas hitherto it was supported upon the fly wheel. The invention, however, is not to be limited to the straight bar form 45 of inertia governor as there are other advantages in the selected location of the governor such as simplicity of construction, improved accessibility and the closer approach of the governor to the center line of the engine.

50 While I have herein shown and particularly described the preferred embodiment of my invention I do not wish to be limited to the precise details of construction shown as changes may readily be made without departing from the spirit of my invention, but having thus described my invention I claim 55 as new and desire to secure by Letters Patent the following:—

60 1. A steam engine including an engine shaft; a shaft driving crank; a carrier upon which are provided two stops and which carrier is mounted upon the crank to turn therewith; and a governor having a member 65 whose range of movement is limited by said stops.

2. A steam engine including an engine shaft; a shaft driving crank; a carrier upon which are provided two stops and which carrier is mounted upon the crank to turn therewith; a governor having an inertia bar also 70 mounted upon the crank; and a spring coupling said inertia bar with said carrier.

3. A steam engine including a piston, a cross head coupled with the piston, a pitman, a crank coupled to the cross head by 75 the pitman, an engine shaft coupled with the crank, a lubricant container in which the cross head, pitman and crank move, and a governor mechanism also movable within the lubricant container and operating as a 80 splashing element to distribute lubricant to other parts of the engine.

4. A steam engine including a piston, a cross head coupled with the piston, a pitman, a crank coupled to the cross head by 85 the pitman, an engine shaft coupled with the crank, a lubricant container in which the cross head, pitman and crank move, and a governor mechanism carried by the crank also movable within the lubricant container 90 and operating as a splashing element to distribute the lubricant to other parts of the engine.

5. A steam engine including a piston; a cross head coupled with the piston; a pitman; a crank coupled with the cross head by 95 the pitman; an engine shaft coupled with the crank; a case inclosing the cross head, pitman and crank and in which case lubricant may be contained to be distributed 100 in the case by the action of working parts therein; a governor within the case and carried by the crank; a reach rod within the case and actuated and controlled by the governor with which the outer end of the reach 105 rod is connected; a rocker arm connected at its lower end with the inner end of the reach rod and having its lower part within the aforesaid case; and a valve rod upon the exterior of the case and connected at its 110 outer end with the upper end of the rocker arm that is also upon the exterior of the case.

6. A steam engine including a piston; a cross head coupled with the piston; a pitman; a crank coupled with the cross head by 115 the pitman; an engine shaft coupled with the crank; a case inclosing the cross head, pitman and crank and in which case lubricant may be contained to be distributed in 120 the case by the action of working parts therein; a governor within the case and carried by the crank; a reach rod within the case and actuated and controlled by the governor with which the outer end of the reach 125 rod is connected; a rocker arm connected at its lower end with the inner end of the reach rod and having its lower part within the aforesaid case, the mounting for the rocker arm being also within the case to receive 130

lubricant; and a valve rod upon the exterior of the case and connected at its outer end with the upper end of the rocker arm that is also upon the exterior of the case.

5 7. A steam engine including a piston, a cross head coupled with the piston, a pitman, a crank coupled with the cross head by the pitman, an engine shaft coupled with the crank, a case inclosing the cross head, pitman and crank, a governor within the case and carried by the crank, a reach rod within the case and actuated and controlled by the governor with which the outer end of the reach rod is connected, a rocker arm connected at its lower end with the inner end of the reach rod and having its lower part within the aforesaid case, and a valve rod upon the exterior of the case and connected at its outer end with the upper end of the rocker arm that is also upon the exterior of the case.

25 8. A steam engine including a piston, a cross head coupled with the piston, a pitman, a crank coupled with the cross head by the pitman, an engine shaft coupled with the crank, a case inclosing the cross head, pitman and crank and in which case lubricant may be contained to be distributed in the case by the action of working parts therein, a governor within the case and carried by the crank, and a reach rod within the case and actuated and controlled by the governor with which the outer end of the reach rod is connected.

30 35 9. A steam engine including a piston, a cross head coupled with the piston, a pitman, a crank coupled with the cross head by the pitman, an engine shaft coupled with the crank, a case inclosing the cross head,

pitman and crank, a governor within the case and carried by the crank, and a reach rod within the case and actuated and controlled by the governor with which the outer end of the reach rod is connected.

10 15 10. A steam engine including an engine shaft, a shaft driving crank upon the inner end of the shaft and from one side of which crank said shaft projects, a crank pin projecting from the other side of the crank and operatively coupled with the piston of the engine, and a governor mounted upon the crank on the crank pin side thereof and operating across the adjacent end of the shaft.

15 20 25 11. A steam engine including an engine shaft, a shaft driving crank upon the inner end of the shaft and from one side of which crank said shaft projects, a crank pin projecting from the other side of the crank and operatively coupled with the piston of the engine, and a governor mounted upon the crank pin and operating across the adjacent end of the shaft.

20 25 30 35 12. A steam engine including an engine shaft, a crank associated with said shaft and including a crank pin, a shaft directly carried by said crank pin eccentric thereto, a valve mechanism, a governor, and a reach rod connected to said valve mechanism, said governor and reach rod having operative connection with said second shaft.

In witness whereof, I hereunto subscribe my name this 16th day of November, A. D. 1915.

CLARENCE E. PRATT.
